UNITED STATES PATENT OFFICE.

LOUIS HAYNE, OF NEW YORK, N. Y.

EASEL-BRACKET.

SPECIFICATION forming part of Letters Patent No. 635,542, dated October 24, 1899.

Application filed February 23, 1899. Serial No. 706,464. (No model.)

To all whom it may concern:

Be it known that I, LOUIS HAYNE, a citizen of the United States, residing in the city of New York, in the borough of Brooklyn and 5 State of New York, have invented certain new and useful Improvements in Easel-Brackets, of which the following is a specification.

This invention relates to an improved easel-bracket which can be conveniently adjusted 10 to any desired height on the easel-frame, so as to form a rigid support for the picture or other article placed thereon; and the invention consists in the combination, with the standard of an easel-frame, of an easel-bracket 15 consisting of a clip applied to said standard and provided with forwardly-extending ears, a bracket-arm pivoted to said ears and provided at its outer ends with means for supporting a picture and at its inner end with a 20 segmental clamp adapted to bind on the standard, and an inclined brace attached to the bracket-arm and adapted to engage the standard, and, furthermore, in providing the standard of the easel-frame with socket-holes and 25 so shaping the lower end of the said brace as that it will readily engage said socket-holes, as will be fully described hereinafter and finally pointed out in the claims.

In the accompanying drawings, Figure 1 30 represents in perspective view an easel with my improved brackets applied to the standards of the same. Fig. 2 is a side elevation of my improved easel-bracket shown as applied to a standard and drawn on a larger 35 scale. Fig. 3 is an end elevation, partly in section, on line 3 3, Fig. 2; and Fig. 4 is a horizontal section on line 4 4, Fig. 2.

Similar letters of reference indicate corresponding parts. 40 Referring to the drawings, A represents the clip of my improved easel-bracket, which is tightly applied to one of the front standards B of the easel-frame, said clip being provided at its front part with forwardly-extending 45 ears a a, to which is pivoted the bracket-arm C. The arm C is preferably made of sheet metal twisted in a quarter-turn and formed at its front end in a circular loop L for supporting the rod D transversely to the standards of the easel-frame. The middle portion of the arm C is double and riveted together, its pivoted end adjacent to the clip A being

preferably bent at right angles to the middle portion and extended below the pivot, so as to form a segmental clamp C', which binds on 55 the standard B of the easel-frame, so as to exert a clamping action thereon. When the rod D is passed through the loop-shaped ends L of two brackets applied to the two front standards of the easel and a picture placed 60 in position on the arms C, the weight of the picture exerts, by means of the segmental clamps C', a clamping action on the front standards B, so that the brackets would be rigidly supported thereon without further 65 brace devices. For the purpose, however, of preventing the bending of the pivoted bracket-arms C and producing a positive interlocking of the bracket with the standards B of the 70 easel an inclined brace E is used, which is 75 riveted at its upper end to the middle portion of the arm C and made in the shape of a pin e at the lower end, which takes into one of a number of socket-holes b, that are arranged in the front standards of the easel, as shown 80 clearly in Fig. 2. By the brace E the brackets can be attached at any suitable height on the easel-frame and are able to support even the heaviest pictures, as the twofold action of the clamp and brace retains the bracket in 85 absolute position on the easel-frame.

When it is desired to place the brackets and supporting-rod D higher or lower on the frame, the outer end of each bracket is moved in upward direction, as shown in dotted lines 85 in Fig. 2, so that the clamp and brace are detached from the standard of the easel-frame, after which the bracket can be readily moved higher or lower, so as to bring the same into the desired position. Then the outer end of 90 the bracket is lowered and the brace placed in the corresponding socket-hole, after which the picture can be replaced on the brackets.

The bracket is preferably made of sheet-brass and may be finished in silver or nickel 95 plating and forms a very neat and ornamental bracket for easels of all kinds.

Having thus described my invention, I claim as new and desire to secure by Letters Patent—

1. The combination, with the standard of an easel-frame, of an easel-bracket consisting of a clip applied to said standard and provided with forwardly-extending ears, a

bracket-arm pivoted to said ears and provided at its outer end with means for supporting a picture, and at its inner end with a segmental clamp adapted to bind on the standard, and an inclined brace attached to the bracket-arm and adapted to engage the standard, substantially as set forth.

2. The combination, with the standard of an easel-frame provided with a number of socket-holes, of a clip applied thereto and provided with forwardly-extending ears, a bracket-arm extending from said ears and provided at its outer end with means for sup-

porting a supporting-rod, and at its inner end with a segmental clamp below the pivot, and an inclined brace attached to the bracket-arm and provided at its lower end with a tapering end engaging the socket-holes of the standard, substantially as set forth. 15

In testimony that I claim the foregoing as my invention I have signed my name in presence of two subscribing witnesses.

LOUIS HAYNE.
